UNITED STATES PATENT OFFICE.

ADOLF THALER, OF NEW YORK, N. Y.

DESIGN FOR A PATCHWORK FABRIC-COVERING.

44,501.

Specification for Design.

Patented Aug. 12, 1913.

Application filed June 18, 1913. Serial No. 774,477. Term of patent 7 years.

To all whom it may concern:

Be it known that I, ADOLF THALER, a subject of the Emperor of Germany, residing at New York city, borough of Brooklyn, Kings county, and State of New York, have invented a new, original, and ornamental Design for a Patchwork Fabric-Covering, of which the following is a specification, reference being had to the accompanying drawing, forming part hereof, which represents a plan view of a fabric-covering, showing my new design.

I claim:

The ornamental design for a patchwork fabric-covering as shown.

Signed at New York city, New York, this 17th day of June, nineteen hundred and thirteen.

ADOLF THALER.

Witnesses:

RUTH MEYERS,
MAURICE BLOCK.
